UNITED STATES PATENT OFFICE.

BENJAMIN McINNERNEY, OF COUNCIL BLUFFS, IOWA, ASSIGNOR TO WESTINGHOUSE ELECTRIC & MANUFACTURING COMPANY, OF EAST PITTSBURGH, PENNSYLVANIA, A CORPORATION OF PENNSYLVANIA.

CONTROLLER FOR ELEVATORS.

1,175,368.

Specification of Letters Patent. Patented Mar. 14, 1916.

Application filed August 3, 1912. Serial No. 713,190.

To all whom it may concern:

Be it known that I, BENJAMIN McINNERNEY, a citizen of the United States, residing at Council Bluffs, in the county of Pottawattamie and State of Iowa, have invented a new and useful Controller for Elevators, of which the following is a specification.

My invention relates to improvements in elevator controllers in which station switches are employed and where a period of time should elapse between the operation of any switch to move the controlled mechanism and a starting of the machinery at a future time.

The objects of my invention are:—1. To provide a means of interlocking the various station switches against interference after the operation of any one switch. 2. To provide a means for positively controlling the station switches from the car. 3. To provide means to prevent a loss of control by the initial operator of the station switches except by an operator in the car. 4. A means to clear out any operation of any station switch by a failure of current so that upon a return of the current a switch must be operated anew before there can be a movement of the car. 5. To vary the armature resistance by the least possible number of contacts. 6. To provide a means of controlling the variation of armature resistance by the use of a single series relay. 7. To provide a means for controlling the starting resistance in connection with interlocking the station switches. 8. To control the variation of armature resistance by the combined use of a single series relay and a solenoid involving a time element with means to delay the operation of the starting of the car with reference to the control of the station switches. I attain these objects by the mechanism disclosed in the accompanying drawing, in which—

Figure 1 is a diagrammatic illustration of the entire controller switch-board; Fig. 2 is a diagrammatic illustration of the controller switch-board comprising an automatic slow-down arrangement.

Similar letters refer to similar parts throughout the several views.

The armature of the motor moving the mechanism of the elevator is diagram-

matically represented at A, the shunt field winding at F and an electrical brake solenoid at B. The lines 7 and 5 supply current from any suitable source to be used in the controller mechanism. The solenoid B is adapted to operate a brake upon any suitable part of the driven mechanism. A line switch represented at L is adapted to connect the contact points L' and L'', and the line 7 with the lines B' and F', thereby closing the brake circuit and the shunt field circuits respectively. The solenoid of the up-switch U is arranged to operate the switches k, l and a, for the movement of the armature of the motor to the elevator mechanism in one direction which will be designated as up; the solenoid of the down-switch D is arranged to operate the switches a', l' and k'; for the opposite direction of the armature A for the direction which will be called down. The cores of the solenoid of the reversing switches U and D are mechanically arranged so that at all times when either is operated to close the other cannot be closed. Thus if the switches k, l and a are closed, the switches k', l' and a' held open and the switches k, l and a cannot be closed at the same time that the switches k' and l' and a' are in the same position.

The solenoid b is arranged to operate the controlling switch having the contacts c, c' and c'' and c''' and the interlocking switch i. The core of the said solenoid b has a time element in that it is arranged to be retarded in either direction by any suitable means here shown as dash-pot d. The interlocking switch i has contact points in the lines 4, 6 and 1'. The station relays m, m' and m'' are supplied for each station or stopping place of the elevator car or cage, and may be substantially alike. The station relay m has a brush o adapted to be moved in and out of contact with the conducting sections x and y. The station relays m' and m'' are similarly provided with brushes o' and o'', respectively. The latch p is adapted to hold the brush o in one position out of contact. The lever t is arranged to move the brush o to the position out of contact. The latch p is electrically operated in any suitable manner, as here shown by the solenoid u. The emergency relay n is arranged to electrically

hold the trips w from acting to lift the brushes o , o' and o'' out of contact. The trips w , when released electrically by the relay n , are arranged to move the lever t , to 5 operate the brushes o , o' and o'' of the relays m , m' and m'' to the position designated as out of contact and to the position shown in Fig. 1. When the current energizes the relay n the trips w are moved so as to allow 10 the levers t , t' and t'' to move to permit the brushes o , o' and o'' to take the position in contact. The brush o is arranged to move to the position in contact when the latch p is operated by the solenoid u of the station 15 relay m and m'' , and when the trip w is not released by the relay n . The brushes o' and o'' are similarly controlled by solenoids u' and u'' of station relays m' and m'' . The station relays m , m' and m'' may be of any 20 number equal to the stations from which control is desired. Here only three are shown, it being sufficient to illustrate the apparatus. The station relays m , m' and m'' and any others that may be employed for 25 30 additional stations are arranged to be relatively adjusted so their distances apart may be made proportional to the distances between the stations from which the machinery is to be controlled. Two conducting sections x and y are arranged with an insulating section xy interposed. The movement of the sections x , y , with the insulating section xy is arranged proportional to the movement of the car of the operated mechanism, and in the same directions relative 35 to the relays m , m' and m'' . Upon one of the moving sections as y , a brush 1^x makes contact to transmit current to the section y for movement of the car in one direction as 40 up; and upon the moving section x the brush 2^x makes contact to transmit current to the section x for movement of the car in the other direction as down. The sections x and y are each of sufficient length and 45 travel so that the brushes o and o'' of the station relays m and m'' may respectively be upon the section with the brushes 1^x and 2^x to connect them.

CF¹, CF² and CF³ represent station 50 switches or push buttons on the car. F¹, F² and F³ represent station switches at the stations in multiple with the station switches on the car and are each respectively arranged to connect the line 6 with 55 the lines F^{1x} and F^{2x} and F^{3x}. The lines F^{1x}, F^{2x} and F^{3x} are connected to the station relays m , m' and m'' , respectively, the said relays m , m' and m'' being also each connected to the line 5^{xx}. In the line 5, may 60 be placed the door switches b^1 , b^2 and b^3 for each station in series so that, when the switches are closed, the line 5 is connected with 5^{xx}. The emergency switch 4^e is upon the car and connects the lines 4 and 4^x, 65 breaking connection between them when op-

erated. Limit switches 1 t and 1 t' may be placed in the lines 1 and 1^x and 2 to 2^x, respectively. A slack cable switch 5^c may be placed in the line 5^x and 5^{xx}.

In series with the solenoid b of the controlling switch is placed a single series relay r for short circuiting a resistance e also in series with the solenoid b . It is largely by a combination of the series relay r and a controlling switch involving time regulation that enables me to dispense with a large number of series relays involving a multiplication of parts and contacts and that enables me to simplify to the greatest extent my controlling apparatus. It is obvious that the use of the controlling switch having the solenoid b , and the series relay r for controlling the operation of a motor may be used independently of a multiplicity of station switches and would be adapted to be used in case only one operating switch were employed, in which event the interlocking switch i may be omitted from the controlling switch having the solenoid b .

The provision for a mechanical means for clearing up the various station switches and the use of a current to hold off the means for mechanically rendering the station relays ineffective, enables me to provide in my structure a positive means of making the whole system of control subject to operation anew in case of a failure of current or accident.

To this system of control may also be added a slow-down element. Referring now to Fig. 2, the brushes o , o' and o'' of the station relays m , m' and m'' respectively, are provided with suitable contacts os , os' and os'' . The line o^{5x} completes the circuit through the solenoid of the switch 10 to the line 7. The solenoid 10 is adapted to close the circuit in line 7 to 11, and when the circuit through the solenoid 10 is broken, the circuit through the line 12 is closed. In the line 12 is placed a suitable switch 14, which is arranged to close the armature circuit through the resistance sd in Fig. 2. Line 12 and the resistance sd and the armature are all in multiple circuit. Upon the conducting sections x and y and adjacent to the insulating section xy , are placed raised portions x' and y' , or the said conducting sections x and y are formed having the raised portions x' and y' , respectively, adapted to change the position of the brushes o , o' and o'' as they approach the insulating piece xy , when the slow-down is used in connection with the system of control.

The operation of my system may be described as follows: The current being supplied upon the lines 5 and 7 upon the operation of any station switch, the circuit is completed through the line 7, the line 3, and the emergency relay n . The emergency relay n is in series with the station switches

CF¹, CF², CF³, F¹, F², F³ and the station relays *m*, *m'* and *m''*. The relay *n* operates to lift the trips *w* so that one of the brushes *o*, *o'* and *o''* of the station relays will be operated by energizing the solenoid *u* of the station relay *m*, *m'* and *m''* corresponding to the station switch operated. The energizing of the emergency relay *n* is accomplished by completing the circuit through the line 10 4^x, the emergency switch 4^e and the line 4. The emergency switch 4^e being closed the circuit is then completed through the line 4, the interlocking switch *i* and the line 6. If any one of the station switches CF¹, CF², 15 CF³ on the car, or the station switches F¹, F², F³ at the stations is closed, the circuit will be complete through the line 6 and one of the lines F^{1x}, F^{2x}, F^{3x}. Assuming that the station switch F³ or CF³ is closed by the 20 operator, the circuit will then be completed through the line F^{3x}, and the station relay *m* and the solenoid *u* will operate to drop the brush *o* upon the conductor *x* and the circuit will be completed through the lines 25 5^{xx}, 5^x and the out-line 5. The brush *o* having dropped upon the movable conductor *x*, a circuit will be completed through the line 4, the interlocking switch *i*, the line 1^x, the solenoid of the line switch L, the 30 solenoid of the up switch U, the line 2, the line 2^x, the brush *o*, the lines 5^{xx}, 5^x and 5. It is assumed that all of the door switches in the line 5 are closed. If any one of them is open, the operation of any station switches 35 as F³, F² or F¹ will be ineffective. The closing of the circuit by the dropping of the brush *o* in contact with the conducting section *x* will operate the line switch L, connecting the contact points L⁷ and L⁸ and the 40 lines 7 with the lines r^x, B^x, F^x. The current through the up switch U will operate to close the switches *a*, *l* and *k*. It will be noted that the switches F³ and CF³ are the highest switches in the series and result in 45 energizing the up switch U to close the switches *a*, *l* and *k*. The disposition of the apparatus was thus made for a movement of the car toward the switch operated, or in an upward direction. Upon the closing of the 50 switch *k* and the line switch L, the circuit is completed through the lines B^x, the brake B, the line B^{xx}, B^x and through the switch *k* to the line 5, thereby releasing the brake B. A circuit is also completed through the 55 shunt field F and the armature A. A circuit is also completed from the line 7 through the solenoid *b* of the controlling switch, the resistance *e*, the line 8 and the switch *k* to the line 5. This operates the 60 controlling switch having the contact points *c*, *c'*, *c''*, *c'''*, and also operates the interlocking switch *i* to break the circuits through lines 4 and 6, and 4 and 1^x. The operation of the controlling switch having a solenoid *b* involves a time element. The 65 core of the solenoid *b* is arranged to be retarded in both directions in any suitable manner, here shown by a dash-pot *d*. The energizing of the solenoid *b* closes the switch at the contact *c* after a sufficient time 70 has elapsed and in the same manner successively closes the switch on the contacts *c'*, *c''*, *c'''*. When the controlling switch having the solenoid *b* is moved to contact with the points *c*, *c'*, *c''* and *c'''*, a circuit is 75 closed through the line r^x and through the series relay *r*, as well as through r^{xx} and the resistances *f*, *g* and *h*; and when the current is sufficiently strong, the series relay *r* will open, thus throwing into the circuit of the 80 solenoid *b* the resistance *e*, and thereby regulating the movement of the core of the solenoid *b* of the controlling switch. When the switch *a* is closed by the operation of the up switch U a circuit is completed which extends from line 7 through the line switch L, relay *r*, line r^{xx}, the resistances *f*, *g* and *h*, the lines c^x, the switch *a*, the line a^x, the armature A, the line a^{xx} and the switch *k* to the line 5. The series 85 relay *r* being in the circuit of the armature resistance, it will be operated only when the current reaches a predetermined value. As the armature accelerates, the current falls below such value and the series relay 90 *r* closes and further operates to close the successive contacts *c*, *c'*, *c''* and *c'''*. When the current through the solenoid *b* of the controlling switch operates it to make contact, with the point *c*, the resistance *f* is 95 short circuited and the resistance *g* and *h* are left in series with the armature. Likewise, when the points *c'* and *c''* are brought in contact, by the energizing of the solenoid *b*, with the bar of the controlling 100 switch, the resistances *g* and *h* are short circuited. And when the bar of the switch operated by the solenoid *b* makes contact with *c'''* the whole of the armature resistance is short circuited and the circuit is 105 completed from the line 7 through the line switch L, the line r^x, the series relay *r* and the point of the controlling switch *c'''*, the line 9, the switch *a*, the line A^x, the armature A, the line a^{xx} and the switch *k* 110 to the line 5. The motor is gradually speeded up by thus successively cutting out the armature resistances. By the operation of the controlling switch having the solenoid *b*, the interlocking switch *i* is opened. The interlocking switch *i* thus renders inoperative any of the station switches F¹, F², F³; or CF¹, CF², CF³ so that it is impossible after the starting of the motor and 115 attached mechanism to take it away from the first operator by the attempted operation of any station switch and the car will travel toward the floor switch F³ or toward the station represented by the car station switch CF³. When the car has reached the 120 125 130

station to which it was called by the operation of the station switch F^3 or CF^3 , the conducting strip x will have moved so that the brush o of the station relay m is moved 5 upon the insulating strip xy , breaking the connection between the line 1^x , and the line 5^{xx} , whereupon the circuit through the line switch L will be broken and the car will stop. Upon operating another station 10 switch as F^2 or CF^2 the circuit will then be established through the line 3, the relay n , the lines 4^x and d , interlocking switch i , line 6, line F^{2x} , the relay m' , line 5^{xx} , line 5^x and line 5. The brush o' will then be 15 thrown in contact with the conducting strip x and the circuit established through line 1^x , the line switch L , the down-switch D , the lines 1, 1^x , 5^{xx} , 5^x and 5. This will operate the line switch L to close on the 20 contacts L^7 and L^r and the down-switch D to close the switches a' , k' and l' . The armature circuit will thus be established in the opposite direction to that just heretofore described and a circuit will be established 25 from the line 7 through the line switch L , the series relay r , the line r^{xx} , the resistances f , g , h , the line 9, the switch a' , the line A^{xx} , the armature, the line a^x , through the switch k' and the line 5. Circuit 30 will also be established through the line 7, the solenoid b , the resistance e , the line 8, B^s , and through the switch k' to the line 5, thereby energizing the solenoid b to operate the controlling switch in the 35 same manner as heretofore described, closing on the contacts c' , c'' , c''' and opening the interlocking switch i . As the controlling switch having the solenoid b is operated to close against the contacts c' , c'' , c''' , the resistances f , g and h are 40 respectively short circuited. As the resistances f , g and h are short circuited by the operation of the controlling switch connecting the points c' , c'' , c''' , the current 45 will be increased through the line r^x , and the series relay r until it operates the switch, throwing the resistance e into series with the solenoid b , retarding the movement of the core of the solenoid b . As heretofore 50 described, when the movement of the car was assumed in the other direction, the operation of any station switch after the interlocking switch i has been opened, will be ineffectual. The car will then be moved 55 toward the station switch, which has just been operated until the insulating piece xy has moved under the brush o' , of the station relay m' ; unless the circuit is otherwise broken, and the car will stop at the 60 station to which it was called by the operation of the station switch.

In stopping the car at any intermediate place other than the station to which it is called by the operation of the proper station switch, and for retaining control by

the operator in the car, the emergency switch 4^e is employed. Assuming that the up-switch U is closed, closing the switches k , l and a , and that the car is moving toward the station controlled by the floor switch F^2 , then the insulating piece xy will be somewhere between the brushes o and o' . If the operator opens the emergency switch, the circuit through relay n , the lines 4^x , 4 and 1^x , the line-switch L , the up-switch U , 75 the line 1 , 1^x , 5^{xx} , 5^x and 5 , will be broken and the armature and brake circuits will be broken and the car will stop. The circuits of the solenoid of the relay n , having been broken, the trips w will be released and will 80 lift the brushes o' , o'' and o and the whole switch-board will be cleared.

It will be observed that when the interlocking switch i is opened, the circuit through the lines 4 and 1^x after the operation of either the up-switch U or the down-switch D the controlling circuit is completed by the switches l or l' , respectively, so that the circuit through the emergency relay n , the solenoid of the line switch L and 90 either the up or down switch is maintained after the interlocking switch i has rendered ineffective the station switches. Thus by operation of the emergency switch 4^e the operation of any station switch will immediately be rendered ineffectual. In event of the operation of a station switch exactly simultaneously with a station switch upon the car, one or the other of said switches will control, depending upon the disposition 95 of the up and down or reversing switches. The operator in the car can clear the switch-board by the operation of the emergency switch and thereupon by again operating the proper switch upon the car control the operation. In event of the operation of two oppositely disposed station switches as F^3 and F^1 or F^3 and CF^1 , simultaneously, the car will move toward the station corresponding to one or the other of the station 100 switches operated, as F^1 , depending upon the disposition of the reversing switches. When the insulating piece xy has lifted the brush as o'' corresponding to the station to which the car has been called, the circuit 105 will then be broken and the car stopped. The breaking of the circuit through the brush o'' of the station relay m'' corresponding to the station to which the car has been called as heretofore described deenergizes the solenoid of the reversing switch as D , allowing the reversing switch as D to fall and open the switch l' , breaking the circuit through the emergency relay n , allowing the trips w to lift any of the remaining brushes o or o'' that may be down, 110 clearing up the board and preventing a return of the car to the station whose oppositely disposed switch has been simultaneously operated. It will be readily ob- 115 120 125 130

served that due to the time element of the non-interference switch i , before the same is closed and when two station switches oppositely disposed have been operated simultaneously, one of the reversing switches either U or D will have operated to have broken the circuit through the switch l or l' and the emergency relay n . It will be apparent that switches placed between the lines 1 and 1^x , if operated at the limits of travel of the car, will open the line switch and stop the car. In a like manner, a limit switch placed between the lines 2 and 2^x at the down limits will operate in the same way to stop the car at the end of its down travel. The circuit of the shunt field F is also controlled by the line switch L, the circuit being completed through the lines 7, F^x , and F^{xx} to the line 5. In a similar manner, if the station switch F^x or CF^x be operated, the up-switch U will be closed and, unless otherwise stopped, the car will move upward until the insulation piece xy moves proportionately with the car to its limit when the circuit through the brush o'' and the line 1^x will be broken and the car stopped and the board cleared. The operation of either of the remaining switches F^2 , CF^2 , F^3 or CF^3 will start the car back with the same regulation and control as described.

It will readily be seen that between the time the emergency switch 4^e has operated or the insulating section xy has broken the circuit, the controlling switch having the solenoid b will require some time to leave the contacts c''' , c'' , c' and c and close the interlocking switch so the car can be moved by the operation of a station switch at any other station. It also gives time to open doors and prevent loss of control. By holding the emergency switch open the operator in the car can prevent interference from any station.

In the system illustrated in Fig. 2, when any one of the station relays m , m' or m'' have one of their brushes o , o' or o'' in contact with the conducting sections x or y and not upon the raised portion thereof, x' or y' , the particular brush will make contact with the contact point os , os' or os'' as the case may be. Thus as the brush o is in contact with either of the conducting sections x or y , it will also be in contact with the contact piece os and the solenoid 10 will be energized. When the solenoid 10 is energized, the circuit through the line 7 is closed and the circuit through the line 12 is broken. As the circuit through the line 12 is broken, the switch 14 opens and the slow-down resistance sd is cut out of the armature circuit. The closing of the circuit in the line 7 at 11 operates to energize the solenoid b of the controlling switch having the contacts c , c' , c'' and c''' . This results in gradually cutting out successively the resist-

ances f , g and h in the armature circuit in the same manner as heretofore described, bringing the motor up to its normal running speed. Assuming that the brush o is in contact with either of the conducting sections x or y , as described for operation of the car, when either of the moving conducting sections x or y has traveled so that the brush o is upon the raised portions x' or y' , respectively, and as the insulating piece xy approaches the brush o , the brush o will be thrown out of contact with the contact piece os , and the solenoid 10 will be deenergized, the circuit through the line 12 will be closed, the solenoid of the switch 14 will then be energized from the armature circuit and the switch 14 be closed throwing the slow-down resistance in multiple with the armature circuit. The deenergizing of the solenoid of the switch 10, at the same time that it energizes the solenoid of the switch 14, breaks the circuit of line 7 at 11 and deenergizes the solenoid b of the controlling switch. Thus it will be seen that by the breaking of the circuit between the brush o and the contact piece os , the slow-down resistance sd is cut into the armature circuit tending to dynamically brake the same, and at the same time cuts in the resistances f , g and h into the armature circuit, producing a dynamic slow-down. A further movement of the conducting sections x and y and the insulating piece xy , brings the brush o on to said insulating piece xy , thus breaking the control circuit as heretofore described and thereby stopping the car.

What I claim is:

1. In an electric system for a traveling car or mechanism; a plurality of selectively operable station relays and switches, and means comprising an emergency relay for rendering all of said station relays mechanically inoperative upon cessation of current in said emergency relay circuit.
2. In an electric operating system for a traveling car or mechanism; a plurality of station relays and switches, and an emergency relay mechanically rendering all of said station relays ineffective upon cessation of current in said emergency relay circuit and a non-interference switch interlocking said station switches.
3. In an electric operating system for a traveling car or mechanism; a plurality of station relays and switches; an emergency relay mechanically rendering all of said station relays ineffective upon cessation of current in said emergency relay circuit, and a time controlled non-interference switch interlocking said station switches.
4. In an electric system for a traveling car or mechanism; a plurality of station relays and switches, an emergency relay, and mechanical means controlled by said relay for rendering all of said station relays inef-

- fective upon cessation of current in said emergency relay circuit, and dynamic braking means controlled by said station relays.
5. In an electric operating system for a traveling car or mechanism; a plurality of station relays and switches, an emergency relay, mechanical means for rendering all of said station relays ineffective upon cessation of current in said emergency relay circuit, 10 and a non-interference switch interlocking said station switches.
6. In an electric operating system for a traveling car or mechanism; an electric motor, a plurality of station relays, as emergency relay, mechanical means for rendering all of said station relays ineffective upon cessation of current in said emergency relay circuit, a time controlled non-interference switch for interlocking said station 15 switches, and a dynamic braking circuit for said motor controlled by said station relays.
7. In an elevator system, the combination with a plurality of selectively operable station relays and switches, of mechanical 20 means for rendering all of said relays inoperative, and electro-responsive means for controlling said mechanical means.
8. In an elevator system, the combination with a plurality of selectively operable station relays and switches, of mechanical 25 means for locking said station relays in an inoperative position, and a relay for controlling said mechanical means.
9. In an elevator system, the combination with a plurality of selectively operable station relays and switches, of mechanical 30 means for simultaneously rendering all of said relays inoperative, and an emergency relay for controlling said mechanical means.
- 40 10. In an elevator system, the combination with an electric motor, a plurality of station relays for selectively controlling said motor, a plurality of station switches and a corresponding number of car switches for controlling said relays, means for rendering said station relays inoperative, and means for interlocking said station switches.
- 50 11. In a system of control for a traveling car or mechanism, an electric motor, a switch arm for controlling the motor circuit, a plurality of station relays and switches, a non-interference switch for interlocking said station switches and means controlled by said station switches for controlling said switch arm and said non-interference switch.
- 60 12. In a system of control for a traveling car or mechanism; an electric motor, a switch arm for controlling the motor circuit, a means having a time element for operating said switch arm, and means whereby the strength of the current in the motor circuit automatically influences said time element control; a plurality of station relays and 65 switches, and a non-interference switch connected to said switch arm for interlocking said station switches.
13. In an electric operating system for a traveling car or mechanism; a plurality of station switches, a plurality of station relays adapted to be operated by said station switches, an emergency relay, mechanical means for rendering all of said station relays ineffective upon cessation of current in said emergency relay circuit, and an emergency switch to break such relay circuit. 75
14. In a controller for an electrically driven car or mechanism, an electric motor, a controlling switch adapted to vary the armature circuit and having a time element; a series relay adapted to automatically influence said controlling switch, a plurality of station switches and relays for controlling the said controlling switch, an electrically released emergency relay, a switch for controlling the emergency relay and a non-interference switch operated by said controlling switch adapted to render all station switches ineffective after the operation of one of said switches during movement of the car and for a period thereafter. 80
15. In an elevator system, the combination with an electric motor, a resistor in circuit therewith and controlling means for said resistor, of a plurality of station relays and station switches, means for interlocking said switches, and means controlled by said switches for actuating said controlling means and said interlocking means. 85
16. In an elevator system, the combination with an electric motor, a resistor in circuit therewith and controlling means for said resistor, of a plurality of station relays and station switches, a switch for interlocking said station switches mechanically connected to said controlling means, and electro-responsive means for actuating said controlling means. 90
17. In a system of control for an electrically driven mechanism, an electric motor, an electrically operated controlling switch adapted to vary the motor circuit and having a time element; a series relay adapted to automatically influence the controlling switch and station switches, and means in connection with said controlling switch for rendering ineffectual the operation of the station switches after the operation of any one of said station switches. 95
18. In a controller for an electrically driven car or mechanism, an electric motor, a controlling switch adapted to vary the motor circuit and having a time element; a series relay adapted to automatically influence said controlling switch, a plurality of station switches and relays, an electrically released emergency relay and switch, and a non-interference switch operated by said controlling switch. 100
19. In a controller for an electrically 105

driven car or mechanism, an electric motor, a controlling switch adapted to vary the motor circuit and having a time element; a series relay adapted to automatically influence said controlling switch, a plurality of station switches and relays, an electrically released emergency relay and switch, a non-interference switch operated by said controlling switch, and reversing switches 5 for controlling said controlling switch.

20. In a controller for an electrically driven car or mechanism, an electric motor, a controlling switch adapted to vary the motor circuit and having a time element, a series relay adapted to automatically influence said controlling switch, a plurality of station switches and relays, an electrically released emergency relay and switch, a non-interference switch operated by said controlling switch, and reversing switches 10 for controlling said controlling switch.

20. In a controller for an electrically driven car or mechanism, an electric motor, a controlling switch adapted to vary the motor circuit and having a time element, a series relay adapted to automatically influence said controlling switch, a plurality of station switches and relays, an electrically released emergency relay and switch, a non-interference switch operated by said controlling switch, and a brake circuit for said motor controlled by said station relays. 15

21. In a controller for an electrically driven car or mechanism, a controlling switch adapted to vary the motor circuit and having a time element, a series relay adapted to automatically influence said controlling switch, a plurality of station switches and relays, an electrically released emergency relay and switch, a non-interference switch operated by said controlling switch, and a slack cable switch in series 20 with said station switches.

ference switch operated by said controlling 30 switch, and electro-responsive means for controlling said controlling switch.

22. In a controller for an electrically driven car or mechanism, a controlling switch adapted to vary the motor circuit 35 and having a time element, a series relay adapted to automatically influence said controlling switch, a plurality of station switches and relays, an electrically released emergency relay and switch, a non-interference switch operated by said controlling 40 switch, and hatch door switches in series with said station switches.

23. In a controller for an electrically driven car or mechanism, a controlling 45 switch adapted to vary the motor circuit and having a time element, a series relay adapted to automatically influence said controlling switch, a plurality of station switches and relays, an electrically released 50 emergency relay and switch, a non-interference switch operated by said controlling switch, and a slack cable switch in series with said station switches.

BENJAMIN McINNERNEY.

HENRY PETERSON,
ETHEL H. INGRAHAM.

Corrections in Letters Patent No. 1,175,368.

It is hereby certified that in Letters Patent No. 1,175,368, granted March 14, 1916, upon the application of Benjamin McInnerney, of Council Bluffs, Iowa, for an improvement in "Controllers for Elevators," errors appear in the printed specification requiring correction as follows: Page 2, line 15, strike out the word and reference-letter "and *m*"; page 6, line 14, claim 6, for the word "as" read *an*; and that the said Letters Patent should be read with these corrections therein that the same may conform to the record of the case in the Patent Office.

Signed and sealed this 18th day of April, A. D., 1916.

[SEAL.]

R. F. WHITEHEAD,

Acting Commissioner of Patents.

Cl. 172—152.
